UNITED STATES PATENT OFFICE

170,116

SPOKE AND HUB COVER FOR AUTOMOBILE STEERING WHEELS

Hinch G. Gilliam, Kingsport, Tenn.

Application March 9, 1953, Serial No. 23,954

Term of patent 14 years

(Cl. D14—30)

To all whom it may concern:

Be it known that I, Hinch G. Gilliam, a citizen of the United States, residing at Kingsport, State of Tennessee, have invented a new, original, and ornamental Design for a Spoke and Hub Cover for Automobile Steering Wheels, of which the following is a specification, reference being had to the accompanying drawing, forming a part hereof.

Fig. 1 is a perspective view of a spoke and hub cover for automobile steering wheels showing my new design;

Fig. 2 is a top plan view;

Fig. 3 is a bottom plan view; and

Fig. 4 is a side elevational view thereof.

I claim:

The ornamental design for a spoke and hub cover for automobile steering wheels, substantially as shown.

HINCH G. GILLIAM.
